2,639,724

REFRIGERATED LIQUID DISPENSING UNIT

Abraham J. Cohen, Samuel Levine, Morris Caminear, and Stephen S. Price, New Haven, Conn.

Application September 1, 1950, Serial No. 182,826

3 Claims. (Cl. 137—334)

1

This invention relates to a refrigerated liquid dispensing unit, and has for one of its objects the production of a simple and efficient refrigerated unit for dispensing carbonated water, beverages, beer, and other liquids, under a constant pressure, in a manner to avoid formation of bacterial growth, and thereby facilitate the serving of one or several sanitary and refrigerated beverages of superior quality at all times.

A further object of this invention is the production of a simple and efficient valve control mechanism for a refrigerated liquid dispensing unit to facilitate the selective dispensing of one beverage, or a combination of several beverages, the dispensing unit itself being refrigerated by means of a refrigerant circulating through said unit.

Other objects and advantages of the present invention will appear throughout the following specification and claims.

In the drawing:

Figure 1 is a top plan view of the refrigerated liquid dispensing unit;

Figure 2 is an irregular vertical sectional view thereof taken on line 2—2 of Figure 1;

Figure 3 is a fragmentary top plan view;

Figure 4 is an irregular horizontal sectional view through the unit, certain parts being shown in top plan view;

Figure 5 is a fragmentary bottom plan view of the unit, certain parts being shown in section to illustrate the communication between the entrance port and the primary reservoir; and

Figure 6 is a detail sectional view taken on line 6—6 of Figure 1.

By referring to the drawing, it will be seen that 10 designates the housing of the dispensing unit which is supported upon a hollow cylindrical support 11 having a threaded end 12. The threaded end 12 is adapted to engage a suitable means for anchoring the support 11 in place in any conventional manner, to hold the flange 13 of the housing 10 against a suitable wall W, shown in Figure 2. The housing 10 is provided with a suitable circular or spiral refrigeration receiving channel 14 formed in any desired manner, to encircle the housing near its outer periphery, as shown in Figures 2 and 4, so as to encircle the control valves. The channel 14 receives the refrigerant from the feed tube 15 and the refrigerant is relieved through the return tube 16. The tubes 15 and 16 extend longitudinally within the cylindrical support 11 to the channel 14 of the housing 10 to provide circulation for the coolant such as brine solution or

refrigerants, or a combination of both. Any suitable means may be utilized to pass and control the passage of the coolant through the tube 15, the channel 14 and return tube 16.

10 The housing 10 carries an inner portion 17, as shown in Figure 2, and a vertically arranged downwardly tapering socket 18 is formed therein adjacent the inner side of the housing 10, as shown in Figure 2. The lower end of the socket 18 is provided with a port 19 which communicates with a transversely extending passage 20. The passage 20 extends across the center of the housing 10, as shown in Figure 5, and communicates at its opposite end with the cylindrical reservoir 21 of a primary dispensing element, by means of a port 22 of the casing 23. The lower end of the casing 23 is closed by means of a nut 24. The casing 23 is also provided with an upper chamber 25, and a port 26 provides a communication between the reservoir 21 and the upper chamber 25. The upper end of the chamber 25 is closed by a nut 27 and a valve stem 28 passes through the nut 27, the chamber 25 and into the reservoir 21. Bearings 29 are preferably carried by the nut 27 for contact with the valve stem 28, as shown in Figure 2, to facilitate reciprocation of the valve stem 28. A resilient valve washer 30 is carried by the valve stem 28 below the port 26, and a coil spring 31 is also carried by the stem 28 intermediate the nut 24 and the valve washer 30 to normally close the port 26. A tappet head 32 is carried by the upper end of the stem 28 for engagement with the cam under face 33 of the nose 33^a of the actuating lever 34.

40 A selected liquid, beverage, or the like is fed under pressure to the socket 18 through the port 35 from the supply pipe 36. The pipe 36 may be provided with a suitable valve at a suitable location to control flow through the pipe 36. This is common to all dispensers. A guide nut 37 is threaded into the upper end of the socket 18 and carries an adjusting plug 38 which is adjustably threaded through the nut 37. The 45 plug 38 carries an inverted cone-shaped or tapered end portion 39 at its lower end to regulate the volume of flow of liquid, beverage, or the like, from the pipe 36 and through the socket 18 to the passage 20. This plug 38 is set by the operator to obtain a desired flow and may be adjusted when necessary to enlarge or diminish flow merely by threading the plug 38 through the nut 37.

The actuating lever 34 is carried by the shaft 40 and this shaft 40 is journaled at its ends in

the upstanding journals 41 carried by the top of the housing 10. The shaft 40 extends transversely of the housing 10 and at right angles to the longitudinal axis of the cylindrical support 11. A shield casing 42 encases the lower end of the actuating lever 34 and is carried by the housing 10. The upper end of the lever 34 extends through the aperture 35 of the casing 42, as shown in Figure 2.

When the actuating lever 34 is pulled in forward direction, the valve stem 28 is depressed against the tension of the spring 31, and the valve 30 is moved away from the port 26 to open this port. Liquid or beverage under pressure will then pass from the reservoir 21, which is supplied through port 22 from the passage 20, and pipe 36. The liquid or beverage will thereafter pass into the chamber 25 out through the port 44 and then into chambers 45 in a downward direction and out through the lower open ends of the chambers 45. The chambers 45 are placed inwardly and laterally of the casing 23 and upon opposite sides of the passage 20—see Figure 5.

A supporting member 46 is carried by the lower end of the housing 10 and supports a downwardly tapering dispensing nozzle 47, having an open discharge end or exit port 48. An outer nozzle 49 is supported in encasing and spaced relation relative to the nozzle 47 and is provided with an open discharge end or exit port 50 below and surrounding the end 48 of the nozzle 47. Venturi orifices 51 in any desired number, are formed in the nozzle 49 near its upper end, as shown in Figure 2.

As the liquid or beverage under pressure passes from the chambers 45, it will pass through exit port 48 and exit port 50. This action will set up an ejector action between the inner and outer nozzles 47 and 49 thereby mixing the liquid or beverage with the atmosphere and with air which is drawn through the Venturi orifices 51. As stated above, the orifices may be in any desired number. When the actuating lever 34 is returned to its upright and normal position, the valve 30 will close the port 26 and shut off the liquid flow through the valve seat or port 26 and the exit ports 48 and 50.

The housing 10 is provided with laterally spaced twin dispensing units T and T^a having sleeves 52 which support the chambers 45, and a filler 53 is carried within each sleeve 52. Each filler 53 is provided with a cylindrical reservoir 54. The reservoir 54 of one filler 53 communicates with a supply pipe 55, and the reservoir 54 of the companion filler communicates with the supply pipe 56, as shown in Figure 4. The pipes 55 and 56 supply selected liquids or beverages under pressure and carry conventional valves to open and close flow through the pipes in the conventional manner. A nut 57 is threaded into the upper end of each reservoir 54 of the filler 53, and a threaded guide nut 58 is threaded vertically through the nut 57. A valve stem 59 is extended vertically through each guide nut 58, which nut 58 is provided with suitable bearings engaging the stem 59 to facilitate reciprocation of the stem 59 through the nut 58. A housing 60 is carried by each filler 53 and extends downwardly through the open end of the chamber 45 thereof. The stem 59 carries a needle valve 61 at its lower end which normally extends through the outlet port 62 formed at the lower end of the housing 60. A valve head 63 is carried by the lower end of the valve stem 59 and is provided with a suitable washer to overhang the edges of

the port 62 and provide an efficient seal to normally close the port 62. A coil spring 64 is interposed between the lower end of the guide nut 58 and the valve head 63 to normally hold the valve head 63 in a port closing position. The position of the guide nut 58 may be adjusted to regulate the tension of the spring 64.

The actuating lever 34 is provided with a pair of oppositely arranged laterally extending portions 65 and 66 arranged to overlie the laterally spaced stems 59 of the auxiliary twin dispensing elements or units T and T^a. A ball 67 is carried by the upper end of each stem 59. The upper end of each stem 59 under the ball 67 fits into a suitable notch 68, and the ball 67 of each stem 59 overhangs the edges of the companion notch 68, as shown in Figures 2 and 3. The ball 67 of each stem also fits in a suitable recess 69 formed in each of the portions 65 and 66, above the companion notches 68, as shown in Figure 2. As the lever 34 is swung forwardly, the stems 59 of the twin dispensing units T and T^a will be lifted to open the respective ports 62.

The supply pipe 36 is preferably provided with a suitable control valve 36^a at a suitable location and the pipes 55 and 56 are provided with similar valves 55^a and 56^a respectively, to open and close the flow through the pipes at the will of the operator to supply one or a combination of liquids, syrup, beverages, and the like.

When the stems of the elements or units T and T^a are lifted to open the ports 62, liquid from pipes 55 and 56 will flow into the reservoir 54 under pressure if both valves 55^a and 56^a are opened, the down through the housings 60, and out through the ports 62 through the dispensing openings 48 and 50 in the same manner as previously described. If only the valve 56^a is opened the liquid will be dispensed only through the unit T. If only the valve 55^a is opened liquid will be dispensed only through the unit T^a. By opening all three valves 36^a, 55^a, and 56^a, a mixture of three beverages or liquids may be obtained when the actuating lever 34 is swung forwardly to open the port 26 as well as the ports 62 of the units T and T^a. When only the valve 36^a is opened and the actuating lever 34 is swung forwardly thereby opening the port 26, the liquid or beverage or the like is dispensed from the supply line through the dispensing or exit ports 48 and 50 as set forth above.

From the foregoing description it will be understood that the volume flow through the passage 20 to the reservoir 21 is controlled through the medium of the adjustable plug 38, and the kind of liquid dispensed is controlled by manually operating a selected valve 36^a, 55^a, or 56^a. Only one kind of liquid or beverage may be dispensed, or a combination or mixture of two or more may be dispensed through the refrigerated housing 10. Any number of dispensing units may be provided by adding more dispensing units.

It further should be understood that certain detail changes in mechanical structure may be made within the spirit of the present invention so long as these changes fall within the scope of the appended claims.

Having described the invention, what we claim as new is:

1. A liquid dispensing unit of the class described comprising a housing, said housing having a cooling agent receiving channel, said housing having a liquid receiving socket, means for regulating the flow of liquid through the socket, means for supplying liquid under pressure to said

socket, a dispensing element in said housing and having a reservoir communicating with said socket for receiving liquid under pressure from the socket, said element having a chamber provided with a port communicating with said reservoir, a normally closed valve controlling the flow of liquid from the reservoir to the chamber, said housing having means for dispensing liquid from said element when said valve is opened, a plurality of auxiliary dispensing elements carried by said housing offset laterally and rearwardly of the first mentioned dispensing element; each auxiliary dispensing element having a reservoir, a discharge valve mechanism for each auxiliary reservoir, said valve mechanism comprising a valve stem and a discharge port normally closed by the valve stem, a rocker lever mounted on a horizontal pivot above said dispensing elements, means carried by the last mentioned valve stem engageable with said rocker lever for opening said port to dispense liquid from said auxiliary reservoir, means carried by said rocker lever for engaging said valve of said first mentioned reservoir to simultaneously open the valves of all dispensing elements as said rocker lever is swung in one direction, and means for supplying a selected liquid to each dispensing element.

2. A liquid dispensing unit of the class described comprising a housing, said housing having a cooling agent receiving channel, said housing having a liquid receiving socket, means for regulating the flow of liquid through the socket, means for supplying liquid under pressure to said socket, a dispensing element in said housing and having a reservoir communicating with said socket for receiving liquid under pressure from the socket, said element having a chamber provided with a port communicating with said reservoir, a normally closed valve controlling the flow of liquid from the reservoir to the chamber, said housing having means for dispensing liquid from said element when said valve is opened, a plurality of auxiliary dispensing elements carried by said housing offset laterally and rearwardly of the first mentioned dispensing element; each auxiliary dispensing element having a reservoir, a discharge valve mechanism for each auxiliary reservoir, said valve mechanism comprising a valve stem and a discharge port normally closed by the valve stem, a rocker lever mounted on a horizontal pivot above said dispensing elements, means carried by the last mentioned valve stem engageable with said rocker lever for opening said port to dispense liquid from said auxiliary reservoir, means carried by said rocker lever for engaging said valve of said first mentioned reservoir to simultaneously open the valves of all dispensing elements as said rocker lever is swung in one direction, means for supplying a selected liquid to each dispensing element, spring means for normally holding the valves of the auxiliary dispensing elements in a closed position, each valve stem of the auxiliary dispensing elements having a ball at its upper end, the actuating lever having notches for receiving the last mentioned valve stems, the balls

overhanging the edges of the notches to connect the last mentioned valve stem to the rocker lever, said valves of said auxiliary dispensing elements being movable upwardly to an open position as said rocker lever is swung in an opening direction, the valve of said first mentioned dispensing element being depressible downwardly to an open position, and means carried by said rocker lever for engaging said first mentioned dispensing element to open the first mentioned dispensing element at the same time as said rocker lever is swung in an opening direction.

3. A liquid dispensing unit comprising a housing, a dispensing element carried by said housing, a normally closed depressible valve for controlling the discharge of fluid from said dispensing element, a pair of auxiliary dispensing elements carried by said housing, a normally closed upwardly movable valve for controlling the discharge of fluid from each auxiliary dispensing element, means communicating with all of said dispensing elements and providing a common discharge for said elements, a rocker lever pivotally mounted on said housing outwardly of said elements, said rocker lever having a portion projecting to one side of the pivot of said lever and overhanging said first mentioned dispensing element, a second portion carried by said rocker lever and projecting beyond the opposite side of said lever pivot and contacting said auxiliary dispensing elements for simultaneously opening the valves of all of said dispensing elements as said rocker lever is swung in one direction, a separate selectively controlled supply means leading to each separate dispensing element to facilitate the selective dispensing of individual and mixed liquids, a dispensing nozzle carried by said housing to receive the fluid dispensed from said dispensing elements and having a discharge end, an outer nozzle encasing said dispensing nozzle in spaced relation thereto and having a discharge end encircling and below the discharge end of said first mentioned dispensing nozzle, and said outer nozzle having Venturi orifices formed therein inwardly of its discharge end thereby providing vents through which air is drawn in a manner whereby an ejector action is set up by the discharge of liquid through the discharge end of the first mentioned nozzle to mix air with the liquid passing out through the discharge end of the outer nozzle.
